STOP MOTION FOR KNITTING MACHINES

Edward J. Ziock, Oakland, Calif.

Application December 19, 1938, Serial No. 246,574

2 Claims.

(Cl. 66—159)

The present invention relates to improvements in stop motions for knitting machines and is herein disclosed as embodied in a circular spring needle knitting machine generally known as the sinker burr wheel machine.

The primary object of the invention is to produce a novel and improved yarn and fabric stop motion which will be sensitive and certain in operation without at the same time imposing any appreciable burden on the yarn or fabric.

Another object of the invention is to provide a yarn stop motion particularly adapted for use in a machine of this type, which will act rapidly and efficiently when thrown into operation to render the knitting elements inoperative and thereafter to stop the machine.

With these objects in view, the several features of the invention consist in the devices, combinations and arrangement of parts hereinafter described and claimed, and together with the advantages to be obtained thereby, will be readily understood by one skilled in the art from the following description taken in connection with the accompanying drawings. Only so much of the machine is disclosed in the drawings as is necessary to show the connection of the present invention therewith.

In the drawings, Fig. 1 is a plan view of a portion of a sinker burr wheel machine illustrating particularly one yarn feed with cooperating knitting elements; Fig. 2 is a plan view on an enlarged scale of a portion of the mechanism illustrated in Fig. 1 showing particularly the sinker wheel and the device for severing the feeding yarn; Fig. 3 is a view in elevation taken from the rear of the mechanism illustrated in Fig. 2; Fig. 4 is a detail view in elevation taken on the line 4—4 of Fig. 2; Fig. 5 is a plan view on an enlarged scale of the pressure mechanism illustrated in Fig. 1; Fig. 6 is an elevation taken from the rear of the mechanism illustrated in Fig. 5; Fig. 7 is a plan view on an enlarged scale of a portion of the stop mechanism illustrated in Fig. 1; Fig. 8 is a view in elevation taken from the rear of the mechanism illustrated in Fig. 7; Fig. 9 is a view in elevation taken from the side of the parts shown in Fig. 7; Fig. 10 is a detailed plan view illustrating particularly a portion of the timing mechanism in operation; Fig. 11 is a similar view to Fig. 10 with the parts shown in position at the end of the movement; Fig. 12 is a sectional view in side elevation taken on the line 12—12 of Fig. 7; Fig. 13 is a plan view on an enlarged scale of the whole detector mechanism illustrated in Fig. 1; Fig. 14 is a view in

elevation taken from the rear of the mechanism illustrated in Fig. 13; Fig. 15 is a detailed plan view of the delayed switch utilized to supply current during the operation of the machine; Fig. 16 is a view in side elevation of the parts shown in Fig. 15; Fig. 17 is a detail view of the mercury dash pot utilized in giving a delayed movement to the switch; Fig. 18 is a plan view taken on the line 18—18 of Fig. 17; Fig. 19 is a view in elevation of the yarn feeler and drop wire mechanism; Fig. 20 is a view in elevation taken from the side of the part shown in Fig. 19; and Fig. 21 is a sectional view in side elevation taken on the line 21—21 of Fig. 13.

15 The sinker burr wheel knitting machine which forms the preferred embodiment of the present invention, comprises a large circular spring needle machine provided with a number of yarn feeds which are distributed at different points 20 on the knitting ring. Loop wheels are utilized to direct the feeding yarn under the beards of the needles and then up into the needle hooks, after which landing wheels operate to raise the old cloth toward the tip of the needle beards. At 25 the same time, the beards are closed by the action of the presser so that the continued rotation of the landing wheel causes the old loops to be cast off over the ends of the needles. The new loops are then finished by one or a number 30 of finishing wheels in the usual way.

Due to the high speed of operation attained with these machines and also the comparatively great weight of the moving parts, much difficulty has been experienced in providing a yarn stop motion which will act promptly and efficiently 35 to prevent damage to the machine or the fabric. This object is attained in the present instance by means of an electrically actuated stop mechanism which acts to sever the defective yarn and then to move the presser out of contact with the needle beards to prevent the fabric from being cut off of the needles from the point where the feeding yarn has been discontinued. These parts are actuated in timed relation to the rotation of the needle cylinder so that a short yarn end of fairly constant length is certain to be produced which will not interfere with the following feeds or otherwise cause injury to the machine.

40 50 Owing to the fact that it is undesirable to permit the landing and sinker wheels to run into the needles for any length of time when no fabric is being produced, mechanism is also provided which is thrown into operation by the yarn stop motion to throw the machine starting and stop-

ping switch into neutral position so that the whole machine is brought to a standstill within a few revolutions.

The machine is also provided with a novel and improved fabric hole detecting mechanism which comprises a number of small feelers grouped together which make contact with the fabric and act upon detecting a flaw in the fabric to return the starting and stopping switch of the machine to neutral position.

Referring more specifically to the drawings, a portion of a grooved ring is indicated at 22 rigidly secured to a horizontal plate 23 of the machine frame, and forms a mounting for the knitting and feeding elements cooperating with the spring beard needles 24. The presser lever is indicated at 26, a sinker wheel of ordinary construction at 28, and the yarn eye through which the yarn is fed to the needles, at 30. The feeding yarn 32 passes from the supply through a knot-catching device 33 (see Figs. 1, 19, and 20), vertically upward over a trip lever 34 to an eyelet 36, over the anvil plate 38 for the yarn severing hammer 40 and thence to the yarn eye 30.

The feeler mechanism for throwing the yarn stop motion into operation (see Figs. 19 and 20) comprises a yarn contact lever 42 which is mounted on a fixed pivot 44 and is normally held in a substantially vertical position by the feeding yarn at a point between the trip lever 34 and the knot-catching device 33 which may be conveniently located adjacent to the yarn supply; as indicated, the knot catcher 33 comprises a gauging hole in a plate. In order to insure that no appreciable burden is imposed on the yarn, the yarn contact lever 42 is provided with a number of contact fingers 46 which cooperate with a series of fingers 48 formed on a bracket rigidly mounted on the machine frame so that the yarn during the normal operation of the machine is fed between the two groups of fingers. At its lower end the lever 42 is provided with a short arm from which is suspended the contact wire 50 of a mercury switch 52, which for the vertical position of the lever 42 is out of contact with the mercury. But when the contact lever 42 is released and permitted to fall forward, the contact wire 50 is depressed to close the switch. The trip lever 34 is normally held in the position illustrated in full lines in Fig. 19 by contact with the tip of a bell crank lever 54 which is pivotally mounted at 56 on a bracket 58. The bell crank lever 54 is held in position to support the trip lever 34 by means of a small tension spring 60 which is stretched between the free arm of the bell crank lever and a short lever arm 62 which is held adjustably in position on a fixed pivot 64. The movement of the bell crank lever 54 under the influence of the spring 60 is limited by a stop 66 adjustably secured by a pin and slot connection 68 to the machine frame. When the tension on the feeding yarn is unduly increased by the catching of a defective yarn in the knot catcher 33, the bell crank lever 54 will yield against the pressure of the spring 60, thus releasing the trip lever 34 and allowing the yarn to slip out from between the two sets of contact fingers 46 and 48 to release the yarn contact lever 42 and so close the switch 52 to energize a circuit for causing a cessation of the machine activities in a manner hereinafter described.

With this construction, a sufficient amount of slack is provided in the feeding yarn to insure the operation of the yarn severing device before

any injury to the machine can result from the catching of the feeding yarn.

Where there is a break in the feeding yarn, the release of the yarn contact lever 42 acts equally to throw the yarn stop motion into operation and causes the presser to be thrown out of operation before the fabric is cast off from the needles.

The mechanism for actuating the hammer to sever the yarn and for throwing the presser out of active engagement with the needle beards is actuated in timed relation to the rotation of the needle cylinder and comprises a disk 70 pivotally mounted at 72 on a bracket 74 which is mounted to swing on a vertical stud 76 on the machine frame. A tension spring 78 stretched between a point on the bracket 74 and an arm 80 rigidly secured to the stud 76 holds the disk yieldingly in engagement with the needles, so that the disk 70 is given a continuous rotary movement in timed relation to the movement of the needle cylinder. A cam disk 82 is loosely mounted on the pivot 72 and may be operatively connected to move with the disk 70 by the engagement of a pawl lever 84 pivotally mounted on the lower disk 82 with ratchet teeth 86 rigidly secured to the disk 70. During the normal operation of the machine, the cam disk 82 remains in a stationary position, the pawl lever 84 being held out of contact with the ratchet teeth against the pressure of a tension spring 88 by the engagement of the hooked end of a locking lever 90 mounted on the fixed pivot 92 with corresponding projection formed on the pawl lever 84. The lever 90 is normally held in locking position with its free end out of contact with an electromagnet 94 by means of a tension spring 96 stretched between a point on the lever and a point 98 rigid with the machine frame. When the electric circuit including the magnet is closed by the action of the feeler mechanism upon discovery of a flaw in the yarn, the end of the locking lever 90 is drawn towards the magnet, thus unlocking the pawl lever 84 and permitting it to swing under the influence of its spring 88 into engagement with the ratchet teeth 86 to cause the disk 82 to rotate with the continuously rotating disk 70. The disk 82 is provided with two cam surfaces comprising a pin 100 and a cam 102 which are adapted respectively to throw into operation the mechanism for severing the yarn and for moving the presser lever out of engagement with the needle beards.

When the disk 82 is rotated, the pin 100 comes into contact with and acts through the lever 104 mounted on the fixed pivot 106 and the intervening connections to trip the hammer 40 illustrated in Figs. 2 and 3 to sever the thread. The lever 104 is connected at its lower end through a link 110 to the lower end of the latch lever 112 which is loosely mounted to turn on a pivot 114. The upper end of the latch lever 112 is provided with a notch 116 which is normally held in engagement with a pin 118 on the hammer 40 by the action of a spring 120 coiled about the pivot 114. The hammer is pivoted at 122 on a fixed bracket 124 and is forced yieldingly in a direction to engage with the anvil 38 by means of a spring 128 coiled about the pivot 122. The movement of the lever 104 and the link 110 causes the latch lever 112 to swing about its pivot to disengage the pin 118 from the notch 116 and permits the hammer to fall and sever the yarn.

In order to prevent the yarn from jumping ahead when the tension is released by the severing operation and so interfering with the proper

operation of the sinker burr wheel 28 in feeding the yarn to the needles, a yarn take-up has been provided in the form of a drop wire member 127 hinged on a fixed portion of the machine and adapted to engage the feeding yarn against a plate 128 at a point adjacent to the yarn eye. As shown in Figure 2, the plate 128 is provided on an element 129 mounted on the anvil plate 38, and has its upper face in alignment with the tensed yarn adjacent the eye 30. The member 127 is intermediately hinged to the element 129 for swinging beneath it in an upright plane, and has a terminal bend or loop 131 extending upwardly from one end and freely through a complementary slot 133 provided in the plate 128 for receiving the yarn through it for the support of the member 127 by the yarn portion engaging the upper face of the plate for a frictional engagement of the yarn with the loop and plate thereat. A weight 135 is slidably adjustable along the arm of the loop 131 for adjusting the gravity pull of the member 127 transversely against the yarn and the resulting degree of friction. The other end of the member 127 is arranged to engage the under side of the plate 38 as a stop means to so limit the lowering of the loop when the yarn is broken or cut as to provide a U bend in the yarn to frictionally restore the original tension of the yarn for its continued feeding to the knitting mechanism.

The continued rotation of the disk 82 set in motion by the mechanism for detecting flaws in the yarn now causes the presser lever 26 to be thrown out of operation in timed relation to the rotation of the needle cylinder to prevent the fabric from being cast off of the needles after the short end of the severed yarn has been used up. The cam 102 carried on the disk 82 engages with one arm of a bell crank lever 130 mounted on the fixed pivot 106, which acts through the connecting link 132 secured to the free end of the bell crank 130 to release the latch lever 134 loosely mounted on the fixed pivot 136. The presser lever is mounted to turn on a fixed pivot 138 and is held in engagement with the needle beards by means of a hand lever 142 which is mounted to turn on the pivot 143 and carries at one end an adjustable screw 144 adapted to bear against the presser lever 26. The latch lever 134 is adapted to hold the lever 146 pivotally mounted at 148 in position to lock the spring pressed lever 150 against movement about the fixed pivot 143 under the pressure of its spring 152. The lever 150 is provided with a short arm 154 which for this position of the lever 150 is adapted to engage and lock the hand lever 142 in position to hold the presser in contact with the needle beards. When the yarn stop motion is thrown into operation, the latch lever 134 is actuated as above described to release the locking lever 146 which in turn swings about its pivot 148 and permits the spring pressed lever 150 to rotate about the pivot 143 a quarter turn into engagement with the hand lever 142, causing it to turn on its pivot and permitting the presser 26 to be withdrawn into the position illustrated in dotted lines in Fig. 5.

The continued rotation of the disk 82 for causing the yarn to be severed and the presser to be withdrawn from contact with the needle beards in timed relation to the rotation of the needle cylinder, brings the pawl lever 84 into contact with a stationary cam 156 to disconnect the pawl lever from the ratchet teeth 86 and stops the rotation of the disk 82. The parts at this point in

the operation are at the positions illustrated in Fig. 11. Before setting up the machine, the operator must again return the disk 82 manually to its original position illustrated in Fig. 7.

5 Mechanism is also provided which is thrown into operation by the closing of the switch 52 in the operation of the yarn stop motion as above described and acts to return the starting and stopping lever, or hand-shipper 158 of the machine to neutral position to stop the machine. This mechanism (Figures 1 and 13 and 14) comprises a magnet 160 which is rendered active by the closing of the switch 52 to release a latch lever 162 which is loosely mounted on a fixed pivot 164 and is held normally in open position during the operation of the machine. The latch lever 162 is adapted to hold a locking lever 168 pivotally mounted at 170 in position to lock the lever 172 against movement about its pivot 174 under the pressure of a spring 176. When the latch lever 162 is actuated by the closing of the electric switch 52, the locking lever 168 is permitted to swing back to release the spring pressed lever 172 which swings about its pivot 174 and strikes the lever 178 which is loosely mounted on the pivot 174 and acts through the connecting rod 180 to release the latch 162, thus permitting the return of the hand-shipper member 158 to its neutral position which is indicated in dash lines in Figures 1 and 16. The machine will now come to a gradual stop as friction overcomes the inertia of its moving parts.

In order to prevent injury to the magnets from the heavy current used in operating the yarn stop mechanism, mechanism is provided for breaking the circuit upon stopping the machine. A delayed switch is provided for this purpose which is thrown into operation in returning the shipper lever 158 to a neutral position but which does not operate to break the circuit until after the machine has finally come to a stop, so that current is at all times available to operate the yarn stop motions on the remaining active feeding yarns if necessary while the machine is slowing down. This mechanism comprises a switch bar 184 pivotally mounted at 186 and having secured at one end the contact wire 188 of the mercury switch 190 and at its other end a weight 192, said switch being connected in series with the circuit of the switch 50—52 and the electromagnets 94 and 160. During the operation of the machine, the switch bar 184 is held in position with the mercury switch 190 closed and the weight 192 in raised position by the contact of the starting and stopping lever 158 with a bent portion of the switch bar 184. When the starting and stopping lever 158 is returned to neutral position, the switch bar 184 is permitted to move about its pivot 186 under the influence of the weight 192 to throw out the switch 190. A delayed movement is given to the switch bar 184 by means of a mercury dash pot 194 which comprises a plunger 196 secured at one end to the switch bar 184 and provided at its other end with a piston head 198 which is loosely fitted within the dash-pot cylinder 194. A series of holes are punched in the piston head to permit the piston to be raised comparatively rapidly when the starting and stopping lever 158 is thrown into operating position. During the downward movement of the piston, these are effectively blocked by a disk or cover 199 which is loosely secured to the underside of the piston head 198.

The present invention also contemplates the

provision of a novel and improved fabric hole stop motion which will act upon detecting holes or imperfections in the cloth to prevent further rotation or knitting of the machine. As usually constructed, fabric stop motions are provided with a single feeler which has been found subject to certain disadvantages. When the feeler is operated at a pressure which will insure the detection of flaws in the fabric, it will often enter enlarged knitted loops as well as the holes caused by imperfect yarns and dropped stitches for which it was intended the machine should stop. Furthermore, the concentration of the pressure at one point tends to roughen and otherwise injure the fabric. In order to provide a hole detecting mechanism which will be sufficiently sensitive to detect imperfections and holes and will at the same time operate with a minimum of strain on the fabric without roughening or abrading the surface, the feeler arm is provided with a number of feeler fingers to bear against the fabric and so to distribute the pressure necessary for the proper operation of the device.

The fabric hole stop motion as illustrated in Figs. 1, 13, 14 and 21, consists of a fabric contact lever 200 to which are secured the small feeler plates 202. Two plates only are shown in the illustrated machine but it is evident that the number and size of the plates may be varied in accordance with the gage and type of knitting being produced. The fabric contact lever 200 is pivotally mounted at 204 on a lever arm 206 which is adjustably secured by means of pin and slot connections 208 to a swivel plate 210, so that the system of levers 200 and 206 can be moved towards or away from the fabric. The swivel plate 210 is rotatably mounted on a pivot 212 about which is coiled a spring 214 which tends to swing the swivel plate 210 and the lever 206 into operative position. The small feeler plates 202 of the fabric contact lever 200 are held yielding in contact with the fabric by means of a small tension spring 216 connected at one end to a rearwardly extending portion of the yarn contact lever 200 and at its other end to an arm 218 rigidly secured on the lever 206. When a defect is encountered in the fabric, the feeler plates 202 will move forward and be caught in the hole causing the lever 206 and the swivel plate 210 to rotate about the pivot 212 into the dotted position illustrated in Fig. 13, when the feeler plates 202 will again disengage themselves from the fab-

ric. This movement of the swivel plate 210 causes a light spring finger 220 mounted on a projecting arm 222 to move into contact with and disengage the latch lever 162 to throw the machine stop motion as above described.

Mechanism is also provided which operates to disengage the latch lever 162 and stop the machine in case the fabric becomes too slack through the failure of the fabric take-up commonly supplied in machines of this type, to function properly. This mechanism comprises a shoe 226 which is secured to the end of a shaft 228 mounted for endwise movement on the bracket 230 and is pressed yieldingly into engagement with fabric 15 by means of a compression spring 232 coiled about the shaft 228 between a collar 234 and a fixed bracket 236. The shaft 228 is provided at its rear end with a hook portion 238 which is adapted to engage a projection on the latch lever 20 162. When the fabric becomes too loose, the shoe 226 and the shaft 228 will be permitted to move forward under the influence of the spring 232 causing the hook portion 238 to release the latch lever 162, thus throwing into operation the mechanism 25 for returning the starting and stopping lever 158 to neutral position to stop the machine.

The invention having been described, what is claimed is:

1. In a knitting machine the combination of 30 knitting elements and a yarn stop motion comprising a yarn contact lever normally supported by the feed yarn, means rendered operative by the fall of the lever to sever the yarn, and a friction means thereafter automatically operative 35 upon the severed yarn portion between the yarn severing means and the knitting elements to provide and maintain a normal feeding tension on said yarn portion.
2. In a knitting machine the combination with 40 knitting elements of a yarn stop motion comprising a yarn contact lever normally supported by the feeding yarn, means rendered operative by the fall of the lever to sever the yarn, means operative upon the yarn between the knitting elements 45 and the yarn severing means for feeding yarn to the knitting elements, and a friction means operative against the yarn between the yarn feeding means and the yarn severing means to maintain a normal feeding tension on the yarn 50 end after the yarn is severed.

EDWARD J. ZIOCK.
